PENCIL SHARPENER

Joseph Ness, Rockford, Ill., assignor to Spengler Loomis Manufacturing Co., Chicago, Ill., a corporation of Illinois

Application June 25, 1932. Serial No. 619,239

9 Claims. (Cl. 120—96)

This invention relates to improvements in pencil sharpeners and more particularly to improvements in pencil sharpeners having automatic feed devices.

- 5 It has been heretofore proposed to clamp and support the pencil to be sharpened and to automatically feed the pencil towards the cutting means by resilient means effective to urge the pencil clamp towards the cutting means.
- 10 Such devices as heretofore disclosed and used have materially complicated the external parts of the pencil sharpeners and the pencil clamp has been generally guided by a fixed part of the supporting frame for the pencil sharpener.
- 15 It is an object of the present invention to provide a more simple and compact arrangement of the automatic pencil feeding mechanism.
- It is further an object of the present invention to slidably support the pencil clamping means by 20 guiding members extending through the chip receptacle which is removably secured to the fixed support of the pencil sharpener in the ordinary manner.
- It is further an object of the present invention 25 to provide tubular guide members extending through the chip receptacle between the end walls thereof which slidably receive guiding rods attached to the pencil clamping means and which also receive resilient means surrounding the guiding rods which react in such a manner as to feed the pencil clamping means towards the cutting mechanism. In this arrangement the resilient feeding means is entirely concealed within the chip receptacle.
- 30 Further objects and advantages of the present improvements will be more readily apparent from the following description taken in connection with the attached drawing in which—

Figure 1 is a side elevation of a pencil sharpener;

40 Figure 2 is an end elevation of the pencil sharpener;

Figure 3 is a detail horizontal section taken on the plane indicated 3—3 in Figure 2 and showing the guiding rods for the pencil clamp in extended relationship in readiness for feeding a pencil towards the cutting mechanism, and

45 Figure 4 is a sectional view similar to Figure 3 showing the guiding rods for the pencil clamp in normal position.

50 Referring to the drawing, the base plate or fixed support 10 carries a head 12. The head 12 carries the conventional rotatable cutters actuated by the handle 14. The chip receptacle, generally indicated 16, is removably attached to the

head 12 by a bayonet joint in the ordinary manner and it is understood that the chip receptacle encloses the rotatable cutters. The chip receptacle has an inner end wall 18 and an outer end wall 20, which are held in spaced relation by the side pieces 22—22. It will be noted that the end wall 18 has a marginal flange 24 while the end wall 20 has a marginal flange 26. The side pieces 22 overlap the marginal flanges 24 and 26 and have end clip portions 28, bent to extend through slots in the end walls 18 and 20 and to be clamped against the inner sides of the marginal flanges 24—26. The enclosure of the chip receptacle is completed by a transparent piece 30 extending between the end walls 18 and 20 and 70 resting against the inner sides of the marginal flanges 24 and 26.

A pair of tubular guide members 32—32 are supported to extend between the end walls 18 and 20, as clearly shown in Figures 3 and 4. The outer ends of the tubular members 32 are provided with head portions 34 forming abutments for the tubes 32 against the end wall 20 and the inner ends of the tubes 32 are beaded over, as at 36, on the outer side of the end wall 18 whereby the tubes 32 are rigidly secured in position.

Slidable within the tubes 32 are a pair of rods 38 which are provided with slotted heads 40 at their inner ends which closely correspond to the inner diameter of the tubes 32 so that they serve to maintain the rods 38 concentric with the tubes 32. The rods 38 are further guided and supported by the head portions 34 of the tubes 32 which form guide bearings 42 closely fitting the rods 38. Compression spring members 44 are carried by the rods 38 within the tubular members 32 and react between the heads 40 of the rods 38 and the bearings 42 of the head portions 34 of the tubular members 32.

It will be apparent, as shown in Figure 3, that when the rods 38 are pulled out in extended relationship with respect to the chip receptacle, that the springs 44 are compressed and tend to return the rods 38 to the normal position shown in Figure 4. In normal position the slotted heads 40 of the rods 38 are in exposed position in order that the rods are accessible for adjustment into threaded engagement at their outer ends 46 with the supporting plate 48 for a pencil clamp or chuck 50. It will be understood that the pencil clamp 50 includes jaw members 52 resiliently urged towards each other to clamp a pencil which may be inserted between the jaws and which are separable by squeezing together the levers 54.

In operation it will be readily apparent that

the pencil clamp means may be drawn outwardly with respect to the chip receptacle against the resistance offered by compression of the springs 44. The pencil may then be inserted between the jaws 52 after separation thereof by operation of the levers 54. Thereupon the pencil will be supported in proper position for automatic feeding towards the rotatable cutters which may be actuated by rotation of the handle 14.

Various modifications may be resorted to without departing from the spirit of the present invention as expressed in the appended claims.

I claim:

15. 1. In a pencil sharpener, a frame, rotatable cutting means supported by said frame, a chip receptacle removably attached to the frame and enclosing said cutting means and automatic means for gripping and feeding a pencil towards said cutting means slidably supported by said chip receptacle independently of said frame.
20. 2. In a pencil sharpener, a frame, rotatable cutting means supported by said frame, a chip receptacle removably attached to said frame and enclosing said cutting means, pencil gripping means, means extending through said chip receptacle for slidably supporting said pencil gripping means on said chip receptacle independently of said frame and resilient means for automatically feeding the pencil gripping means towards said cutting means.
25. 3. In a pencil sharpener, a chip receptacle including a pair of spaced end walls, a pair of tubular members extending between said end walls of said receptacle, a pair of guide rods extending within and slidably with respect to said tubular members, pencil gripping means carried by said guide rods and resilient means enclosed within said tubular members effective to urge said pencil gripping means in a direction towards said chip receptacle.
30. 4. In a pencil sharpener, a removable chip receptacle including a pair of spaced end walls, a transparent side wall, a pair of tubular members extending between the side walls and within said receptacle, a pair of guide rods slidably associated with said tubular members, said rods having enlarged heads closely fitting the interior of said tubular members, a compression spring carried by each of said guide rods within each of said tubular members, said springs being arranged

to react between said tubular members and the heads of said guide rods for moving said guide rods into said tubular members and pencil gripping means carried by said guide rods on the exterior of said receptacle for automatically feeding the pencil into said receptacle through expansion of said springs.

5. In a pencil sharpener, a frame, rotatable cutting means supported by said frame, a chip receptacle enclosing said cutting means, non-rotatable pencil gripping means, means slidably supporting said pencil gripping means by said chip receptacle and resilient means normally effective to urge said pencil gripping means towards said cutting means.

6. In a pencil sharpener, a chip receptacle, a pair of guides fixed with respect to said receptacle, a pair of supports carried by and slidable with respect to said guides, pencil gripping means carried by said supports and resilient means reacting between said guides and said supports effective to urge said pencil gripping means in a direction towards said chip receptacle.

7. In a pencil sharpener, a chip receptacle including a pair of spaced end walls, a pair of tubular members extending between said end walls of said receptacle, a pair of guide rods extending within and slidably supported by said tubular members, pencil gripping means carried by said guide rods and resilient means effective to urge said gripping means in a direction towards said chip receptacle.

8. In a pencil sharpener, a chip receptacle, a pair of guides fixed with respect to said receptacle, a pair of supports carried by and slidable with respect to said guides, pencil gripping means carried by said supports and resilient means effective to urge said pencil gripping means in a direction toward said chip receptacle.

9. In a pencil sharpener, a frame, rotatable cutting means supported by said frame, a chip receptacle removably attached to said frame and enclosing said cutting means, pencil gripping means slidably supported and carried by said chip receptacle independently of said frame and resilient means enclosed within said chip receptacle effective to urge said pencil gripping means in a direction for feeding a pencil towards said cutting means.
